COMBINATION KITCHEN UNIT

Manuel Cecil Kite, 225 Clifton St.,
Oakland, Calif. 94618

Filed Jan. 12, 1966, Ser. No. 574

Term of patent 14 years

(Cl. D33—19)

The back of the unit is of conventional configuration. The dominant features of my design reside in those portions shown in full lines on the drawing.

I claim:

The ornamental design for a combination kitchen unit, substantially as shown and described.
